ROY D. MAILEY, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

ELECTRIC VAPOR LAMP

Application filed February 1, 1924. Serial No. 689,989.

My present invention relates to method and means for starting vapor electric arc devices in which the vaporization of the arc path medium is initiated or accelerated for the purpose of accelerating the starting of the device by means of heat generated with current from the lamp current main or current from an auxiliary source. It relates further to such an apparatus in which the 10 heating coil is automatically deenergized upon the normal operation of the lamp and the flow of a normal or predetermined current therethrough or attainment of normal voltage across the lamp. It relates particularly to starting heating method and means for mercury vapor arc lamps but is applicable in the arts generally.

In starting a mercury vapor lamp of the type of which the lamp is tipped to cause 20 the mercury to flow and form an electrical connection between the electrodes thereof and then tipped back into the normal position an arc is formed between the mercury and the anode as the mercury recedes to its 25 normal position. Upon the striking of the arc usually there is sufficient mercury vaporized thereby and electrons emitted to form a conducting path between the mercury and the anode and to sustain the arc. However, an appreciable amount of time elapses 30 between the formation of the arc in its incipient stage and the development of the normal current path and complete attainment of normal operating characteristics 35 within the lamp. For example in a high temperature quartz mercury arc lamp such as is used for a source of ultra violet light and to which I shall describe the application of my invention in this application the 40 period between the forming of the incipient arc and the attainment of normal operating conditions is in the neighborhood of five minutes. With the use of my invention I am able to cut down this starting period appreciably. In the apparatus of my invention an electric heater which is positioned 45 about the mercury chamber of the lamp is brought into connection with a source of electric current, an electric path is estab-

lished through the lamp by causing the mercury thereof to connect the cathode and the anode by momentarily depressing the anode end of the lamp and the heater is automatically disconnected from such source upon the attainment of normal operating conditions within the lamp.

It is an object of my invention to provide method and means for cutting down the arc establishment time in a vapor electric device.

It is a further purpose of my invention to provide heating means for the mercury chamber of the lamp.

It is also a purpose of my invention to provide means for automatically disconnecting said heating means upon the establishment of desired operating conditions in the lamp.

In the application of my invention as hereinafter fully described I use in one form 70 a solenoid which is connected across the supply mains of a high temperature mercury vapor lamp for disconnecting a heating coil after the lamp is started.

In the drawing which forms a part of this application and in which like numbers refer to like parts is shown a diagrammatic representation of a pivotally mounted mercury vapor lamp having a heating coil connected through a switch across the mains thereof and means for automatically closing said switch upon the tilting of said lamp and the establishing of a current there-through between its terminals and automatic means for disconnecting said heater upon the attainment of normal operating current within the lamp.

In the drawing lamp 1 is mounted on panel 3 which is pivotally fixed at 4 to vertical surface 5. The cathode 12 is connected to the negative main 16 through one side of switch 17, lead 18, inductance 19, lead 20, terminal 22, and lead 21. Anode 14 of the lamp is connected to the positive main 15 through one side of switch 17, lead 26, 95 variable resistance 31, lead 32, terminal 33, and lead 34. The resistance heating coil 2 is connected on one side from the negative

- side of switch 17, through lead 18, lead 23, to terminal 24 and on the other side from the positive side of switch 17, through lead 26, lead 27, contact 28, armature 35, pivot 5 connection 36, lead 41, to terminal 25, the spring 37 fixed at one end to armature 35 on one side of pivot 36 opposite to contact 28 and at its other end at 39 to vertical surface 5 tends to hold said armature 35 in 10 the position in which contact is made between it (armature 35) and contact 28. Across the terminals of the lamp, the solenoid 49 is connected from lead 20 through lead 47 on one side and from lead 32 through 15 lead 48 on its other side. This solenoid when switch 17 is closed and lamp 2 has attained its normal operating characteristics, in which the voltage therethrough has attained its normal value, functions to actuate 20 said armature 35 to move it from the position in which it contacts with contact 28 for the purpose of disconnecting and deenergizing heating coil 2.
- In the operation of the embodiment of 25 my invention shown in the drawing to start the lamp switch is closed and handle 46 of panel 3 depressed to form mercury connection between cathode 12 and anode 14 and then released to start an arc between the 30 mercury 13 and anode 14 as the mercury again flows away from the anode.
- On the closing of the switch 17 heating coil 2 is energized and by heating the mercury 13 of the lamp the starting thereof is 35 accelerated through the rapid production of a vapor mercury path of the required conducting characteristics. As the mercury is vaporized the pressure in the body of the lamp increases with the result that the mercury 40 body 13 is moved into the cathode chamber 42 of the lamp. The solenoid 49 is so designed that the strength thereof upon the movement of mercury 13 into chamber 42 and the increase in the voltage across the 45 terminals of the lamp and consequently across the solenoid attains a value great enough to move armature 35 against spring 37 and from contact with contact 28 whereby the heating coil 2 is deenergized. Said 50 solenoid 49 will continue to hold the heater circuit open as long as normal operating voltage is maintained across the terminals of the lamp but will allow spring 37 to move armature 35 to again close the heater circuit 55 should the voltage drop materially and again in turn open it upon resumption of normal operating conditions in the lamp, while the mains are properly energized and switch 17 closed.
- 60 I claim:
1. The method of starting and operating an electric device of the character described which consists in passing current through said device and through a source of heat 65 therefor, and availing of the change of potential across the terminals of the device to cause the interruption of current to the heater when the device has attained its normal operating temperature.
  2. In combination with an electric vapor 70 device having a positive temperature coefficient of resistance, a source of current therefor, an electric heater connected through a switch across said source of current, means for starting current flow through the device, means tending to hold said switch in the closed position, and means responsive to voltage changes in the device after starting for opening said switch.
  3. In combination with an electric vapor 80 arc lamp, a source of current therefor, an electric heater therefor, connected across the mains thereof, and means responsive to voltage changes across said lamp for automatically rendering said heater inoperative upon 85 the attainment of predetermined or normal operating conditions in said device.
  4. In combination with an electric vapor 90 arc device, feed mains therefor, an electric heater connected across said mains through a switch, and means responsive to voltage 95 conditions in said device for opening said heater switch upon the attainment of normal operating characteristics in the lamp.
  5. In combination with an electric vapor 100 arc lamp, feed mains therefor, means for starting current flow through the lamp, a solenoid connected across the terminals of said lamp, an electric heater about the cathode chamber of said lamp connected to a 105 source of current through a switch which has a magnetic armature in operative relation with said solenoid whereby said switch can be opened by means of said solenoid, and a spring tending to hold said switch in the closed position.
  6. In combination with an electric vapor 110 arc lamp, feed mains therefor, means for starting current flow through the lamp, a solenoid connected across the terminals of said lamp, an electric heater connected across said mains through a switch which is in operative relation to said solenoid whereby said solenoid will operate to open said switch, and a spring tending to hold said 115 switch in the closed position.
  7. In combination with an electric vapor 120 arc lamp, feed mains therefor, means for starting current flow through the lamp, a solenoid connected across the terminals of said lamp, an electric heater for the lamp connected across said mains, through a switch in operative relation to said solenoid whereby said solenoid will operate to open said switch, a spring tending to hold said 125 switch in the closed position, a pivoted support for said lamp, and a spring and stop for said support for holding the support and

lamp in the normal operating position of the lamp.

8. In combination with a vapor electric arc device, a source of current therefor, means for starting current flow through the device, an electric heater therefor, connected through a switch across said current mains, an armature on said switch, means tending

to hold said switch open, a solenoid across said mains of said device and in operative ¹⁰ relation to said armature.

Signed at Hoboken in the county of Hudson and State of New Jersey this 31 day of January, A. D. 1924.

ROY D. MAILEY.
